UNITED STATES PATENT OFFICE.

HARRY F. SMITH, OF LEXINGTON, OHIO, ASSIGNOR, BY MESNE ASSIGNMENTS, TO THE GAS RESEARCH COMPANY, OF DAYTON, OHIO, A CORPORATION OF OHIO.

METHOD OF SUPPLYING MOISTURE TO GAS PRODUCERS.

Application filed November 7, 1917. Serial No. 200,851.

To all whom it may concern:

Be it known that I, HARRY F. SMITH, a citizen of the United States of America, residing at Lexington, Richland County, Ohio, have invented certain new and useful Improvements in Methods of Supplying Moisture to Gas Producers, of which the following is a full, clear, and exact description.

This invention relates to gas producers, and more particularly to supplying the generating chambers thereof with moisture.

In the generation of producer gas the common practice is to pass air and moisture through a bed of incandescent carbonaceous material. The moisture is usually supplied in the form of steam, the proportions of air and steam being regulated in any desired manner, and quite expensive and complicated apparatus is necessary to insure an adequate supply of steam and a proper regulation thereof. One object of this invention is to supply the desired amount of moisture to the generating chamber without the use of steam thus obviating the necessity for such expensive and complicated apparatus.

In carrying this invention into effect water is introduced into the ash pit of the producer in the form of a finely divided spray, which is taken up in a greater or less degree by the current of air flowing through the ash pit to the fuel bed. The moisture thus taken up is carried into contact with the incandescent carbon and there changed into steam. It is obvious that all of the water sprayed into the ash pit may not be carried along by the current of air, but the greater the quantity of spray, the greater will be the quantity of moisture conveyed into the fuel bed. Inasmuch as the character of the gas produced is varied by the relative proportions of air and moisture passing through the fuel bed, it is necessary to provide means for regulating the spray according to the composition of the gas produced so that more or less moisture may be supplied as desired.

In the drawing in which like characters of reference designate like parts:

Fig. 1 is a form of apparatus for carrying my invention into effect, parts thereof being shown in elevation and other parts in section to more clearly illustrate the mechanical details of construction.

Fig. 2 is another form of mechanism for

controlling the amount of spray supplied to the ash pit.

55

In the drawing 1 is a gas producer, which may be of any desired form, having an off-take pipe 2 which connects with the delivery main 3. Extending across the lower part of the producer 1 is a grate 4 of any desired form, which divides the interior of the producer into a generating chamber 5 and an ash pit 6. Opening through the wall of the ash pit 6 is an air inlet 7. As shown the air inlet is freely open at all times, the amount of air passing therethrough into the ash pit and thence into the fuel bed on the grate 4 in the generating chamber 5 being entirely dependent upon the suction caused by exhausters, not shown, located in the pipe 2 between the producer and the delivery main 3. In the conventional producer the exhausters are driven at a speed which varies in accordance with the quantity of gas desired. When a greater quantity of gas is desired, it is merely necessary to speed up the exhausters, thus drawing a greater quantity of air through the port 7 with a resulting increased production of gas in the generating chamber 5. And obviously slowing down the speed of the exhausters results in a decreased production of gas.

70

Leading into the ash pit 6 through the air port 7 is a water supply pipe 8, the flow through said pipe being controlled by the valve 9. Attached to the end of pipe 8 inside the ash pit 6 is a spray nozzle 10 adapted to break up into a finely divided spray any water passing therethrough from the pipe 8. Inasmuch as a current of air is passing through the ash pit from the port 7, through the grate bars and into the generating chamber 5, whenever gas is being generated some part of the spray emitted from the air nozzle 10 will be carried by this current of air into contact with the fuel bed upon the grate 4. It is quite obvious that the quantity of spray thus conveyed depends upon the velocity and quantity of the air current and the quantity of spray present in the ash pit. For a certain air current, however, it is obvious that

75

the moisture conveyed thereby will be dependent upon the quantity sprayed into the ash pit. In other words for a definite air current the quantity of moisture carried through the fuel bed will be varied by vary-

80

105

ing the rate at which the finely divided spray is emitted from the spray nozzle 10. It is thus quite easy to vary the proportion of air and moisture.

- 5 For regulating the quantity of moisture sprayed into the ash pit I make use of controlling mechanism which regulates the flow of water to the spray nozzle 10 in accordance with the composition of the gas produced. In other words I control the valve 9, which regulates the flow of water to the nozzle 10, according to the composition of the gas produced, so that if too much moisture is passing through the fuel bed, this valve will 10 be actuated to decrease the amount of water flowing therethrough, and, if too little moisture is passing through the fuel bed, the valve will be actuated to increase the supply of water passing therethrough.
- 15 20 The mechanism disclosed in Fig. 1 for thus controlling the valve 9 controls the opening of the valve in accordance with the specific gravity of the gas produced. This apparatus is identical in principle with that described in my Patent No. 1397554, dated Nov. 22, 1921. The operation of this regulating device depends upon the fact that as the proportion of moisture passing through the fuel bed increases, the proportion 25 30 of hydrogen in the resulting gas will also increase with a corresponding decrease in the specific gravity of the gas. And conversely that as the proportion of moisture passing through the fuel bed decreases, the proportion 35 40 of hydrogen in the resulting gas will also decrease with a consequent increase in the specific gravity of such gas. This being true it is evident that the specific gravity of the gas in the delivery main 3 is an accurate indication of the proportion 45 50 of moisture passing through the fuel bed.

Leading from the delivery main 3 is a pipe 11 which opens into the lower end of a vessel 12 containing a solution of potassium hydroxide for removing from the gas passing therethrough all carbon dioxide contained therein. This removal of the carbon dioxide is desirable inasmuch as any variation 55 in the proportion of carbon dioxide will also cause a corresponding variation in the specific gravity of the gas. Leading from the upper end of the vessel 12 is a pipe 13, the other end of which is connected to a port 15 in the valve casing 14. Diametrically opposite the port 15 is a port 16, and located midway between these two ports upon opposite sides of the valve casing are two other ports 17 and 18. Leading from the port 16 is a pipe 19 which opens into the lower bell of a gasometer 20. end of which is operatively connected to the actuating stem of the valve 9. Connected to the two ports 17 and 18 are two stand pipes, 24 and 25 respectively. Rotatively mounted in the casing 14 is a valve plug 26 adapted to connect the ports of the casing in pairs. This valve is so actuated as to impart thereto a continually progressive rotary motion which is constant in direction. As a result each one of the pipes 24-25 is connected to the pipe 13 and after any predetermined interval then connected to the pipe 19. From the above description it is obvious that any variations in specific gravity of the gas in the main 3, which can result only from corresponding variations in the generating chamber, will be transmitted to the gasometer 20 to thus actuate the valve 9. And the apparatus is so adjusted that any decrease in the specific gravity of the gas will result in a closing movement of the valve 9, while any increase in the specific gravity of that gas will result in an opening movement of valve 9. This precise regulating mechanism is not essential for a practicing of the invention, but any regulating mechanism governed according to the composition of the gas may be substituted therefor. And a complete and full description of the structure and operation of the regulating mechanism here disclosed is set forth in my above referred to co-pending application.

In Fig. 2 is illustrated a different apparatus for controlling the valve 9, which apparatus is a part of the invention forming the subject matter of my patent No. 1397555 dated Nov. 22, 1921. This regulating mechanism depends for its operation upon the heat value of the gas produced, an abnormal B. t. u. indicating the desirability of decreasing the supply of moisture to the generating chamber, and a subnormal B. t. u. indicating the desirability of increasing the supply of moisture. In the apparatus disclosed 3 is the gas main, through which passes the gas generated in the producer 1, having a pipe 11 opening therefrom for leading off a fraction of the gas. Inserted in the pipe 11 and beyond the pressure regulating valve 27 is a diaphragm 28 having a fixed orifice therethrough. Inasmuch as the pressure at the fixed orifice is constant, because of the pressure regulating valve 27, a constant volume of gas will pass through the orifice to the burner 29 of the calorimeter 30. Located in the calorimeter so that the heat generated by the gas burning therein will impinge thereon, is a closed vessel 31, having a volatile liquid therein and having a pipe 32 leading therefrom to the lower end of an expandible chamber 33. Pivotally connected to one end of this expandible

chamber is a lever 34, operatively connected to the operating stem of the valve 9 by means of an adjustable link 35. Also connected to the lever 34 is a spring 36 adapted 5 to urge the lever 34 to bring about opening movement of valve 9. It is evident that any increase in the heat generated in the calorimeter will cause an increased pressure in the expandible chamber 33 to bring 10 about an elongation of that chamber, with a consequent actuation of the lever 34 to vary the position of valve 9. And it is equally obvious that any decrease in the heat generated in the calorimeter will result in a variation in the opening of valve 9, which variation will be opposite in direction to that caused by the generation of an increased amount of heat in the calorimeter. With the lever 34, adjustable link 15 20 35 and spring 36 so arranged that the valve 9 is positioned to insure a gas of the desired B. t. u. value, it is evident that any variation above or below this predetermined normal B. t. u. value of the gas will 25 result in a corresponding increase or decrease in the opening of valve 9, and in the supply of moisture therethrough, to bring about a return to normal B. t. u.

From the above description it is obvious 30 that the actual quantity of water sprayed into the ash pit 6 is a matter of indifference, it being merely necessary to insure spraying such a quantity of water thereinto that a sufficient amount thereof will be carried 35 through the fuel bed by the air current passing freely through the port 7. In other words it is at no time necessary that the quantity of water being introduced into the ash pit be known. It is only necessary 40 that the flow of water thereinto through the spray nozzle 10 be so regulated that a sufficient quantity of moisture will be carried into the fuel bed. On this account the expensive and complicated regulating 45 mechanism for use where steam is supplied to the generating chamber is entirely unnecessary and the expensive steam generating apparatus for supplying a sufficiently large quantity of steam is also entirely un- 50 necessary. Not only, therefore, is the operation of the moisture supplying apparatus and of the regulating mechanism therefor greatly simplified, but in addition the expense attendant upon the installation and 55 maintenance of such supplying and regulating apparatus is materially decreased.

While the method herein described, and the forms of apparatus for carrying this method into effect, constitute preferred embodiments of the invention, it is to be understood that the invention is not limited to this precise method and forms of apparatus, and that changes may be made in either without departing from the scope of the in-

vention which is defined in the appended 65 claims.

What I claim as new and desire to secure by Letters Patent is:

1. In the generation of producer gas, in which air and moisture are supplied to the generating chamber of the producer, the method of introducing the moisture which consists in spraying water into the air passing to the generating chamber of the producer and regulating the quantity of spray 75 in accordance with the composition of the gas produced.

2. In the generation of producer gas, in which air and moisture are supplied to the generating chamber of the producer, the method of introducing the moisture which consists in introducing water in the form of finely divided spray into the air, passing to the generating chamber of the producer, and automatically regulating the quantity of 80 spray in accordance with the composition of the gas produced.

3. In the generation of producer gas, in which air and moisture are supplied to the generating chamber of the producer, the method of introducing the moisture which consists in spraying water into the ash pit 90 thereof and regulating the quantity of water so sprayed in accordance with the composition of the gas produced. 95

4. In the generation of producer gas, in which air and moisture are supplied to the generating chamber of the producer, the method of introducing the moisture which consists in spraying water into the ash pit 100 thereof and automatically regulating the quantity of water so sprayed in accordance with the composition of the gas produced.

5. In the generation of producer gas, in which air and moisture are supplied to the generating chamber of the producer, the method of introducing the moisture which consists in introducing water in the form of finely divided spray into the air passing to the generating chamber of the producer, and 105 automatically regulating the quantity of water so introduced in accordance with the heat value of the gas produced. 110

6. In the generation of producer gas, in which air and moisture are supplied to the generating chamber of the producer, the method of introducing the moisture which consists in introducing into the air supply 115 thereof, a spray of water, which is in such finely divided particles that substantial 120 quantities of said particles will be mechanically carried along by the air.

7. In the generation of producer gas, in which air and moisture are supplied to the generating chamber of the producer, the method of introducing the moisture which 125 consists in spraying into the air supply water which is so finely divided that the par-

- 4
- 5 ticles thereof will remain in suspension, and be carried along by, the air; and controlling the quantity of spray in accordance with the composition of the gas produced.
- 5 8. In the generation of producer gas, in which air and moisture are supplied to the generating chamber of the producer, the method of introducing the moisture, which consists in spraying into the air supply 10 thereof water which is so finely divided that the particles thereof will remain in suspension, and be carried along by, the air; and controlling the quantity of spray in accordance with the heat value of the gas produced.
- 15 9. In a gas producer, in which a blast of air and moisture is introduced into the generating chamber of the producer during operation thereof; apparatus for introducing moisture into said blast, comprising means 20 for spraying water into the air supply of the producer; and means for automatically varying the quantity of water sprayed into the said air supply to accord with the composition of the gas produced.
- 25 10. In a gas producer, in which a blast of air and moisture is introduced into the generating chamber of the producer during operation thereof, a spray nozzle positioned within the air supply of the producer; means for supplying water to said nozzle for 30 spraying into the air supply, means controlling the quantity of water supplied to said spray nozzle; and means, responsive to variations in the composition of the gas generated, for actuating the said controlling 35 means.
11. In apparatus of the character described, a gas producer comprising a generating chamber, an ash pit below said generating chamber having an air supply opening therein through which air passes into the ash pit and then into the generating chamber of the producer; a spray nozzle positioned within the ash pit; a pipe for supplying water to said nozzle for spraying into said ash pit, a control valve within said pipe; and means responsive to variations in the composition of the gas produced, for actuating the said control valve to govern the quantity of water sprayed into the ash pit, to thus control the amount of moisture taken up by the air passing through said ash pit and carried into the generating chamber of the producer.

In testimony whereof I affix my signature. 55
H. F. SMITH.
